UNITED STATES PATENT OFFICE.

NATHAN BLAIR, OF BUELL, OREGON.

SAWING-MACHINE.

SPECIFICATION forming part of Letters Patent No. 776,989, dated December 6, 1904.

Application filed June 27, 1903. Serial No. 163,369. (No model.)

To all whom it may concern:

Be it known that I, NATHAN BLAIR, a citizen of the United States, residing at Buell, in the county of Polk and State of Oregon, have invented a new and useful Sawing-Machine, of which the following is a specification.

This invention relates to means for actuating one end of a drag or crosscut saw, thus dispensing with the necessity of one of the two operators usually employed.

The object is to provide a structure that can readily be applied to a log or timber to be cut and is easily adjustable to those of different sizes, so that the saw will be properly positioned with relation to its work.

A further object is to provide mechanism that will permit the feed of the saw through the timber, so that said saw will operate with efficiency throughout its entire cut; and a still further object is to employ an actuating-spring that will allow of said proper feed and can be adjusted to obtain any desired tension.

The structure which at present is considered preferable is illustrated in the accompanying drawings, wherein—

Figure 1 is a perspective view of the machine in operative relation to a log. Fig. 2 is a horizontal sectional view through the machine. Fig. 3 is an end elevation of the upper end of the hanger-frame. Fig. 4 is a detail perspective view of the element employed at the connection between the sections of the horizontal frame. Fig. 5 is a cross-sectional view taken on the line 5 5 of Fig. 2. Fig. 6 is a detail sectional view taken on the line 6 6 of Fig. 2. Fig. 7 is a similar view taken on the line 7 7 of Fig. 2.

Similar reference-numerals indicate corresponding parts in all the figures of the drawings.

In the embodiment illustrated a substantially horizontal frame is employed, which is composed of two sections. One of these sections comprises spaced guides 10, secured together at one end by a clip 11 and having their opposite ends connected by an arch 12. The intermediate portions of these guides are curved, as illustrated in Fig. 1. The other section consists of spaced bars 13, pivotally connected by bolts 14 with the guides 10 and

having an arch 15 on an intermediate portion thereof, which arch properly spaces the bars. A hanger-frame is secured to this horizontal frame and is located above the guides. Said hanger-frame consists of inclined bars 16, 55 pivotally secured at their lower ends to the outer ends of the guides, as shown at 17, and having their upper ends spaced apart, said ends being connected by means of a bolt 18 with an adjusting-bar 19, the lower end of 60 which is slotted, as shown at 20, and slides upon one of the bolts 14, connecting the guides and bars 13, as illustrated in Fig. 5. The upper end of the bar 19 has a connection in the form of a brace 21 with one of the bars 16. 65 Between the upper ends of the bars 16 and hung from the bolt 18 is a hanger-bar formed of spaced members 22, that extend between the guides 10 and project some distance below the same. This hanger-bar is provided 70 between its ends with outstanding ears 23, located on opposite sides of the guides, and in the ears is journaled an upright roller 24, located between the guides and coacting therewith. In practice it will be understood that 75 this roller fits rather snugly between the guides and yet is sufficiently loose so that when it is bearing against one of said guides it will be substantially free of the other. The lower end of the hanger-bar 22 is offset, as 80 shown at 25, and to the same is pivoted a link 26, having an upwardly-curved portion 27, that is looped and passed between the members of said bar. The free end of the link carries spaced clevis members 28, adapted 85 to embrace one end of a drag-saw, as 29, being clamped thereon by means of bolts 30.

The sections of the horizontal frame are normally held against their pivotal movement, and to this end a member 31 is employed, 90 which is illustrated in detail in Fig. 4, said member comprising a strip 32, attached to one of the guides 10 and projecting beyond the same, said projecting end having an upstanding curved plate 33, that is located along- 95 side one of the horizontal bars 13. A bolt 34 is passed through the adjacent portion of said horizontal bar, and a clamping-nut 35, threaded upon the bolt, engages the curved plate 33, and thus holds the parts against 100

movement. This member is also provided with an outstanding clamp-plate 36, arranged in a substantially horizontal plane and having ears 37 at its ends. A coiled actuating-spring 38 has its inner end resting upon this plate 36 and secured thereto by another clamping-plate 39, which plate is secured in place by bolts 40, passing through the same and through the ears 37. These plates 36 and 39 constitute adjustable holding means for the spring.

The free or outer end of the spring 38 has secured thereto an upstanding arm 41, having an enlarged upper end 42, in which is pivoted a link 43, the opposite end of the link 15 being downturned and passing through an eye 44, formed upon the hanger-bar 22 contiguous to its upper end.

Suitable means are employed for properly positioning the mechanism with relation to the work to be operated upon. In the present instance an adjustable support is shown in the form of an upright standard 45, having a transverse sleeper 46 at its lower end, provided with feet 47, said sleeper and standard being held against relative pivotal movement by a brace 48 connecting the two. The standard is provided with a longitudinal slot 49, and through the same is passed a bolt 50, that is secured to the clip 11, connecting the guides, said bolt having threaded thereon a clamping-nut 51, arranged to hold the horizontal frame against movement with respect to the standard. The opposite end of said frame is provided with means for attaching the same to a log or other timber, so as to hold the mechanism against longitudinal movement. This means is shown in the form of spuds 52, having offset ears 53, that embrace the bars 13, certain of said ears having set-screws 40 54, that engage the bars to hold the spuds in place. These spuds are adapted to be driven into the log, as illustrated in Fig. 1, and support the adjacent ends of the bars a slight distance above the same. In order to permit this driving action, the upper ends of the spuds project above the upper ears and have heads 55, adapted to be struck with a hammer, ax, or other suitable tool. A saw-guide 56 is also preferably employed in connection with the end of the frame secured to the log. This guide consists of a depending arm 57, having at its upper end offset shoulders 58, that embrace one of the bars 13, the upper end being provided with a set-screw 59, passing therethrough 55 and bearing against the upper edge of the bar 13, which carries the guide. This said guide, which is particularly useful in connection with thin saw-blades and in felling timber, lies alongside of the blade and serves to prevent 60 the same wabbling.

In placing the apparatus in position the spuds are first driven into the log, so that it will be on opposite sides of the cutting-line. The saw being placed between the bars will 65 be on said line. The sections of the horizon-

tal frame are then adjusted to a suitable height, and the outer end of the frame is also properly adjusted. The sawer then grasping the handled end of the saw operates the same in the usual manner. Power will therefore be 7c alternately stored in and transmitted from the spring, and consequently the hanger-bar will be operated. The end of the saw attached to the mechanism will travel in its proper path because of the guiding of the hanger by the 75 roller. As the saw descends during the cutting operation the attached end thereof will gradually feed downward because of the sliding engagement between the bar 19 and the pivot between the sections of the horizontal 80 frame. The result is that said saw will likewise maintain its proper position and the handle end will remain in convenient relation with respect to the operator. The tension of the spring may be readily regulated by the 85 clamp-bar, and because of the link connection between the arm 41 and the hanger-rod said spring does not interfere with the feed of the saw.

From the foregoing it is thought that the 90 construction, operation, and many advantages of the herein-described invention will be apparent to those skilled in the art without further description, and it will be understood that various changes in the size, shape, proportion, and minor details of construction may be resorted to without departing from the 95 spirit or sacrificing any of the advantages of the invention.

Having thus described my invention, what 100 I claim as new, and desire to secure by Letters Patent, is—

1. In a sawing-machine, the combination with spaced guides, of means for adjustably supporting the guides at one end, means for 105 connecting the other ends of the guides with the timber to be cut, a hanger-frame adjustably supported upon the guides, a depending hanger hung from the frame and extending between the guides, said hanger comprising 110 spaced members, an upper and a lower ear attached to the hanger and extending between the members thereof above and below the guides, and a roller journaled in the ears and located at one side of the hanger, said roller 115 having its opposite sides coacting with the guides.

2. In a sawing-machine, the combination with a supporting-frame, of a hanger-frame having a bar pivoted at one end to the supporting-frame and another bar pivoted to the first-mentioned bar and engaging the frame and freely slideable thereon, said bars being spaced apart at their points of connection with the frame, a hanger pivoted to the hanger-frame and freely adjustable thereon, and a saw connected with the hanger, said hanger automatically moving downward as the saw cuts through its work.

3. In a sawing-machine, the combination 130

with a supporting-frame including spaced guides, of a hanger-frame including an inclined bar pivoted to the supporting-frame at its lower end, an adjusting-bar pivoted at its 5 upper end to the supporting-frame and having its lower end engaging the frame and freely slideable upon the same, a hanger swung from the hanger-frame, and a saw connected with the hanger, said hanger and frame automatically moving downwardly as the saw cuts through its work.

4. In a sawing-machine, the combination with a supporting-frame including spaced guides, of a standard for adjustably supporting one end of said frame, means for connecting the other end of the frame to the timber to be cut, a hanger-frame having a pivotal connection at one end with the guides, and a freely-slideable connection at the other end 20 with said guides, a hanger swung from the frame and extending between the guides, and a saw having a link connection with the hanger, said hanger and frame automatically moving downwardly as the saw cuts through its work.

25 5. In a sawing-machine, the combination with a substantially horizontal frame comprising spaced guides, of bars pivotally connected respectively to the corresponding ends of the guides, timber-engaging means carried by the 30 bars, means connecting the bars and guides to hold them against pivotal movement, a vertically-adjustable hanger-frame mounted upon the guides and located above the same, a hanger-bar swung from the frame and extending between the guides, said bar being moved vertically upon the adjustment of the hanger-frame, and a saw-engaging link pivoted to the lower end of the hanger-bar.

6. In a sawing-machine, the combination 40 with a substantially horizontal frame comprising spaced guides, of bars pivotally attached to the guides, an arch-piece located at said pivotal connection, a hanger-frame pivoted upon the guides at one end and having a 45 slideable connection with the horizontal frame contiguous to the connection of the guides and bars, a hanger hung in the frame, and a saw-engaging link pivoted to the hanger.

7. In a sawing-machine, the combination 50 with a supporting-frame comprising guides and spaced bars pivotally connected to the corresponding ends of the guides, of means for preventing the pivotal movement between the guides and bars, an adjustable support for 55 the free ends of the guides, means for attaching the free ends of the bars to the timber to be cut, a hanger-frame mounted on the supporting-frame, a hanger suspended from the

hanger-frame, and a saw connected to the hanger, said hanger automatically moving 60 downwardly as the saw cuts through its work.

8. In a sawing-machine, the combination with spaced guides, of spaced bars pivotally attached to the corresponding ends of the guides, an arch connecting the pivots, another arch connecting the bars, an adjustable support located at the free ends of the guides, timber-engaging jaws located at the free ends of the bars, coacting devices carried by the pivoted ends of the bars and guides for holding 70 said guides and bars against pivotal movement, and a saw movably supported upon the frame.

9. In a sawing-machine, the combination with a substantially horizontal frame comprising 75 sections, of a pivotal connection between the sections, a member secured to one section contiguous to the pivotal connection and having a curved upright plate and a substantially horizontal clamp-plate, a clamping-nut carried 80 by the other section and engaging the upright plate, a saw-actuating spring having one portion resting against the clamp-plate, and a clamping element coacting with said plate and extending across the spring.

85 10. In a sawing-machine, the combination with a substantially horizontal frame comprising spaced curved guides, of an adjustable support attached to one end of the guides, horizontal bars pivotally secured to the other 90 end of the guides, a hanger-frame mounted upon the horizontal frame and located above the same, a hanger-bar suspended from the hanger-frame and extending between the guides, a roller journaled upon the bar and 95 located between the guides, and a link attached to the lower end of the hanger-bar and having means for engaging the saw.

11. In a sawing-machine, the combination 100 with a supporting-frame having spaced guides, of an adjustable support for one end of the frame, work-engaging means located at the other end of the frame, a hanger-frame adjustably mounted on the supporting-frame, a hanger swung thereupon and engaging 105 between the guides, and a saw attached to the hanger, said hanger-frame and hanger automatically lowering upon the supporting-frame as the saw cuts through its work.

In testimony that I claim the foregoing as 110 my own I have hereto affixed my signature in the presence of two witnesses.

NATHAN BLAIR.
